CLAIM

The ornamental design for a cargo carrier, as as shown and described.

DESCRIPTION

FIG. 1 is perspective view of the cargo carrier of the present design;

FIG. 2 is a top view thereof;

FIG. 3 is a bottom view thereof;

FIG. 4 is a front view thereof; and,

FIG. 5 is a right side view thereof.

The broken lines depicting bars on the side of the cargo carrier illustrate environmental structure which forms no part of the claimed design.

The broken lines illustrate portions of the cargo carrier which form no part of the claimed design.
